FASTENING MEANS

Frank E. Stahl, Tonawanda, N. Y., assignor to
Columbus McKinnon Chain Corporation, Tonawanda, N. Y., a corporation of New York

Application December 11, 1935, Serial No. 53,952.
In the Union of South Africa September 7,
1935

4 Claims. (Cl. 152—14)

My invention relates in general to anti-skid devices, and in particular to fastening means which may be used upon the emergency type of anti-skid devices.

5 The principal object of my invention has been to provide a device of this nature which may be inexpensive to manufacture and durable in construction.

Another object has been to provide fastening means having a portion thereof which may be conveniently and inexpensively formed on a wire forming machine.

Moreover, my invention, when being used in connection with the flexible strap of an emergency 15 anti-skid device, may have the clamping member thereof locked by means of the strap.

The above objects and advantages have been accomplished by the device shown in the accompanying drawings, of which:

20 Fig. 1 is a transverse, sectional view of a tire showing my device applied thereto.

Fig. 2 shows a front elevation of a twin chain device, portions thereof being broken away, and

25 Fig. 3 is a front view of my fastening means showing the strap partly broken away.

Fig. 4 is a side, sectional elevation of my fastening means taken on line 4—4 of Fig. 3, showing the clamping means in an inactive position.

30 Fig. 5 is a similar sectional view showing the strap engaged with the buckle part of my device and held in place by the clamping means thereof.

Fig. 6 shows an enlarged, bottom, plan view of my fastening means.

Fig. 8 is a side, sectional elevation of my fasten-

ing means showing a modified arrangement of the clamping means

device comprising a strap securing member 10. The member 10 is of wire and is so shaped as to provide an outwardly extending loop portion 12 at each side thereof, thus providing eyes 13 for the reception of the hooks 14 which connect one of the ends of each of the cross chains 15 to the member. The loop portions 12 are preferably connected together by means of a cross bar 21.

50 This member is also provided with a centrally arranged loop portion 16 which is offset in relation to the loops 12, thereby providing a centrally arranged bar 17 for the reception of one end 18 of the strap 19. This end 18 is formed by passing 55 the strap around the bar 17 and disposing it upon

itself where it may be fastened by rivets 20 or in any other suitable way such as, for instance, by stitching.

My fastening means comprises a chain attaching member 11 which is also formed of wire and which carries the buckle part 35 of my device. This attaching member is provided with outwardly extending loop portions 25 which provide eyes 26 for the reception of hooks 27 which serve to connect the other end of each of the cross chains 15 with the member 11. The member 11 is formed in a manner similar to the member 10 with an offset loop portion 28. This offset loop portion is formed by two parallel arms 29 connected at their outer ends by means of the cross bar 30. The outwardly extending loop portions 25 are connected together by means of a cross bar 31 which, as shown in Fig. 6, is offset inwardly, so as to substantially close the eyes 26 formed by the loop portions 25.

The buckle part 35 of my device is preferably of stamped metal and it is provided with two attaching lugs 36 which extend outwardly from the body portion 37. The body portion is long enough to extend across the attaching member 11 and to engage with the cross bars 30 and 31 thereof. When so positioned, the attaching lugs 36 will be in contact with the parallel arms 29, whereupon the lugs are bent by suitable means around these arms and caused to be firmly engaged therewith, as clearly shown in Figs. 6 and 7. The buckle is, therefore, made a permanent part of the attaching member 11.

The body part 37 of the buckle is formed near the end which contacts with the cross bar 31 with two upstanding bearing arms 40, each of which is formed with a bearing aperture 41. These bearing arms 40 are in parallel arrangement and are formed at the side edges of the body part to provide space for the clamping element 42 which is mounted therebetween. The clamping element is provided with trunnions 43 which are engaged with the openings 41 of the arms. The clamping element is provided with a clamping jaw 44 and with a clamping lever 45. The jaw is so proportioned and positioned that when the strap 19 is in position, as shown in Fig. 5, and the clamping member is brought down to the position there shown, the jaw will contact therewith and will be slightly embedded therein so as to hold the strap firmly within the buckle member. 50

Suitable retaining arms 46 are also carried by the body part and are preferably made from the same material and extended upwardly at substantially right angles to the same. They are 55

arranged at a point on the body opposite to the place where the bearing arms are located and each of them is provided with an inwardly extending lug 47. The retaining arms are so spaced 5 that they provide passage for the strap 19 but the inwardly extending lugs 47 make the space between them so narrow that the strap will be held in place when threaded thereunder. After the strap has been clamped in position, as shown 10 in Fig. 5, the free end 48 thereof is brought around over the top of the clamping lever and passed under the lugs 47 of the retaining arms, as also clearly shown in this figure, whereby the free end will be held down in position and will thus 15 hold the clamping lever in its locked position. The clamping lever 45 is provided near its outer end with notches 49 so that the lever, when being moved to its locking position, may pass in between the lugs 47 of the retaining arms.

20 Obviously, when an emergency anti-skid chain equipped with my invention is to be applied to the tire 50, shown in Fig. 1, the cross chains 15 are placed about the periphery of the tire and the strap 19 is passed under the rim 51 and then 25 threaded through the buckle of my device, as hereinbefore described.

In the modification shown in Fig. 8, I reverse the position of the buckle, having the body 55 so proportioned that the bearing arms 56 thereof 30 will be adjacent the cross bar 30 of the attaching member, and the locking arms 57 will be adjacent the cross bar 31. The attaching lugs 58 of the buckle are, of course, engaged with the parallel arms 29 of the attaching member. The 35 retaining arms 57 have inwardly extending lugs 59, as in the other form of device. In this form of structure, it will be seen that the pull of the strap 19 will serve to more tightly clamp the clamping jaw 44 of the clamping means and will 40 thus hold the clamping lever 45 thereof in contact with the strap. The free end 48 of the strap in this form of invention is returned upon the strap and threaded through between the locking arms 57 and under the lugs 59 thereof.

45 Having thus described my invention, it will be understood that the appended claims should be construed in the light and spirit of the invention as shown in the drawings and described in the specification herein.

50 What I now claim is:

1. Strap fastening means for use in connection with a flexible strap of an anti-skid device, comprising an attaching member formed of wire, and a buckle member superimposed laterally across 55 the attaching member, said buckle member being formed of a sheet metal stamping and provided with means for permanently and rigidly securing it to the attaching member.

2. Strap fastening means for use in connection with a flexible strap of an anti-skid device, comprising an attaching member formed of wire, and provided with outwardly extending loop portions for the tire chains, said attaching member being 5 formed with two interspaced, parallel arms, and a buckle part superimposed laterally across the attaching member, said buckle part having attaching lugs for engagement with the parallel arms of the attaching member for permanently and 10 rigidly securing the buckle part to the attaching member, and a clamping lever pivotally carried by the buckle for clamping and releasing the free end of the strap.

3. Strap fastening means for use in connection 15 with a flexible strap of an anti-skid device, comprising an attaching member formed of wire, and provided with outwardly extending loop portions for the tire chains, said attaching member being formed with two interspaced, parallel arms, 20 and a buckle part superimposed laterally across the attaching member, said buckle part having attaching lugs for engagement with the parallel arms of the attaching member for permanently and 25 rigidly securing the buckle part to the attaching member, a clamping lever pivotally carried by the buckle for clamping and releasing the free end of the strap, and rigid strap retaining means carried by the body adjacent the free end 30 of the clamping lever for engaging and holding the free end of the strap, whereby the free end of the said strap may be returned along the outer face of the lever while the lever is in its clamping position to prevent release thereof.

4. Strap fastening means for use in connection with a flexible strap of an anti-skid device, comprising an attaching member formed of wire, and provided with outwardly extending loop portions for the tire chains, said attaching member being 40 formed with two interspaced, parallel arms connected by a cross bar, and a buckle part superimposed laterally across the attaching member, said buckle part having attaching lugs for engagement with the parallel arms of the attaching member for permanently and 45 rigidly securing the buckle part to the attaching member, a clamping lever pivotally carried by the buckle for clamping and releasing the free end of the strap, and rigid strap retaining means carried by the body adjacent the free end of the clamping lever for engaging and holding the free end of the strap, whereby the free end of said strap may be returned along the outer face of the lever while 50 the lever is in its clamping position to prevent release thereof.

FRANK E. STAHL.
